TO LYON & HEALY, OF CHICAGO, ILLINOIS, A CORPORATION OF ILLINOIS.

PIANO-PEDAL AND LIKE DEVICE.

1,353,755.

Specification of Letters Patent. Patented Sept. 21, 1920.

Application filed March 1, 1919. Serial No. 280,119.

To all whom it may concern:

Be it known that we, BENJAMIN H. JEFFERSON and WALTER I. KIRK, citizens of the United States, residing at Chicago, in the county of Cook and State of Illinois, have invented a certain new and useful Improvement in Piano-Pedals and like Devices, of which the following is a full, clear, concise, and exact description, reference being had 10 to the accompanying drawings, forming a part of this specification.

Our invention relates to piano pedals and like devices.

One of the objects of the invention is to 15 provide a practical and effective form of piano pedal or like device.

Another object of the invention is to provide a construction of piano pedal which may be used by an adult person or by a 20 child or other person with short legs.

Another object of the invention is to secure such an advantageous construction without substantial or undesirable variation from the usual shape of piano pedal now in 25 use.

Another object of the invention is to give ample foothold or space for pressing or acting upon the pedal when employed for either purpose.

Another object of the invention is to accomplish the foregoing and other desirable results in a simple and expeditious manner.

In the accompanying drawings Figure 1 is a front view of the lower part of a piano provided with three pedals embodying our present invention;

Fig. 2 is a cross section taken on line 2—2 in Fig. 3;

Fig. 3 is a view of the under side of the 40 pedal;

Fig. 4 is a cross section of a portion on an enlarged scale taken on line 4—4 in Fig. 5;

Fig. 5 is a cross section taken on line 5—5 in Fig. 4.

Referring to the drawings, we show in Figs. 1, 2 and 3 a portion 1 of the front of a piano case. There are also shown three pedals 2, 3 and 4, which are customarily present in a piano.

In Fig. 1 two of the pedals 3 and 4 are shown in the condition or adjustment in which they may be used by the average adult person, which condition or adjustment will be called the "normal" condition or adjustment. The other pedal 2 is shown in condi-

tion or adjustment to permit of its being used by a child or other short legged person, it being seen that while the pedals 3 and 4 have surfaces 3^a and 4^a, respectively, which may be acted or pressed upon by the 60 foot, the pedal 2 has a surface 2^a which is substantially above the surfaces 3^a and 4^a and therefore capable of being reached by a child or other person whose legs would not extend down far enough to reach surfaces as far down as surfaces 3^a and 4^a. 65

Referring more particularly to the construction of the pedal, we employ a pedal bar 5 which passes through an aperture 6 in the piano case 1, this bar 5 being understood to be connected inside the piano with suitable instrumentalities which are operated by the depression of the bar 5. This bar 5 extends forwardly from the front of the piano case 1, terminating in an end portion 5^a on which the pedal proper is mounted. This pedal 3 is composed of two portions, a portion 7 which may be called the main or body portion, and another portion 8, which may be called the supplemental 75 portion and which is at the rear end of portion 7 and extends upwardly at substantially right angles to the same. The main or body portion 7 is made hollow so that it may fit down over the end portion 5^a of the pedal 80 bar 5 and the front end of this portion 7 is pivoted to the front end of the pedal bar 5^a by means of a pivot or pin 9. Because of this pivotal mounting the pedal 3 may be tilted or swung upwardly and forwardly 90 from the normal position shown in solid lines in Fig. 2 to an elevated position shown in dotted lines in said Fig. 2. In the former position, the pedal may be used in the usual way by resting the foot upon the surface 95 3^a, whereas in the other or adjusted position the foot will rest upon the surface 8^a which is substantially above the surface 3^a when the pedal is lowered.

The pedal bar 5 is provided with a layer 100 10 of felt or other cushioning material which is conveniently wrapped around the rear part of the end portion 5^a. This permits the pedal member 3 to be moved or dropped down into lowered position without making 105 a noise or doing any injury, the body portion 7 of said pedal 3 coming in contact with the felt or cushion material 10.

As a matter of further improvement a stop 11 is provided for limiting the upward 110

and forward adjustment of the pedal, said stop 11 being conveniently secured to the pedal bar end 5^a and located so that the front end portion of the pedal will strike 5 against said stop 11 when the pedal is tilted or swung into its upper position.

As an arrangement for temporarily holding or locking the pedal 3 in either upper or lower position, we show a ball 13 carried by 10 the pedal bar end 5^a, and two apertures 15 and 16 in a plate 17 on the pedal 3, so that the movement of the pedal will locate the ball 13 on one or the other of the apertures 15 and 16 and thereby lock it in such position. The aperture 16 is so located that when the ball 13 is in position in it, the 15 pedal will be in an elevated position, as shown in Fig. 4. The aperture 15 is so located that when the ball 13 is in position 20 in it said pedal will be in a downward position, as indicated in dotted lines in Fig. 4. In order to permit this operation, a plate 19 is secured as by screws 20 to the pedal bar end 5^a and is bent laterally at 21 and 25 then again to form a straight portion 22 substantially parallel with the end 5^a. This end portion 22 is provided with the aperture 14 containing the ball 13. Between the end portion 22 and the end 5^a is located a spring 30 23 which tends to hold said members 22 and 5^a in a separated position and to resist movement of the same toward one another. Thus when the ball 13 is located in either of the apertures 15 or 16 the pedal 3 and pedal bar 35 5 are held in the position to which they are adjusted with a substantial amount of strength, but this may be overcome and a movement of the pedal 3 accomplished to change its adjustment by a quick and strong 40 effort, sufficient to cause the ball 13 to move out of one of the recesses 15 or 16, and overcome the resistance of the spring 23 and thus move to the other of said recesses. Upon arriving at such recess the ball 13 is 45 snapped into such recess by the power of the plate 19 and spring 23, and held in the same with substantial strength, sufficient to permit the proper use of the pedal. Adjustment back to the original position, however, 50 may be obtained by a quick and strong movement of the pedal, sufficient to withdraw the ball 13 from the aperture in which it is located, overcoming the tension of the spring 23 and member 19. As a preferred 55 arrangement the pin 9 is in the form of a threaded spindle which can be screwed into a threaded socket formed in the end portion 3^c of said pedal.

In this way it will be seen that the pedal 60 itself may be used in the ordinary way or may be adjusted so as to provide an elevated pressing surface to permit use by short legged persons. It will also be seen that no outside device or apparatus is required to 65 accomplish this result, the pedal itself being

capable of adjustment to accomplish the desired end.

It will be understood that changes and modifications may be made without departing from the spirit of the invention. 70

What we claim is:

1. The combination of a pedal bar and a pedal attached thereto and provided with a plurality of pressing surfaces.

2. The combination of a pedal bar and a 75 pedal attached thereto and provided with a plurality of pressing surfaces arranged for use at different horizontal levels.

3. The combination of a pedal bar and a 80 pedal attached thereto, said pedal having an adjustable element provided with a plurality of pressing surfaces which are adapted to be brought into operative position by adjustment of said element.

4. The combination of a pedal bar and a 85 pedal attached thereto, said pedal having an angularly adjustable element provided with a plurality of pressing surfaces arranged at an angle to one another, said surfaces being adapted to be brought into operative position 90 by angular adjustment of said element.

5. A pedal device comprising an adjustably mounted pedal member provided with a plurality of pressing surfaces arranged so that by the adjustment of said member 95 said surfaces may be placed in position for use at different horizontal levels.

6. A pedal device comprising a pivotally mounted pedal member having a plurality of pressing surfaces arranged in such position as to be adjustable to different horizontal levels when said member is swung about 100 its pivotal mounting.

7. A pedal device comprising a pedal member having a body portion providing a 105 pressing surface and also having a supplemental portion projecting laterally from one end of said body portion, and providing a supplemental pressing surface.

8. A pedal device comprising a pedal 110 member having a body portion providing a pressing surface and also having a supplemental portion projecting laterally from one end of said body portion, and providing a supplemental pressing surface, and means 115 for adjustably mounting said pedal member so as to permit said supplemental pressing surface to come into position for use at a horizontal position above the level of the body portion pressing surface.

9. A pedal device having a pedal member 120 constructed with a body portion providing a pressing surface and also having a supplemental portion projecting laterally from one end of said body portion, said supplemental portion having a pressing surface lying in a plane substantially at right angles to the plane of the pressing surface of said body portion, and means for pivotally mounting the front end of said body portion so as to 125 130

5 permit said member to be swung upwardly and forwardly to place said supplemental pressing surface in a horizontal position above the level of the main pressing surface when the latter is in position for use.

10 10. A pedal device having a pedal member provided with a body portion lying normally in a substantially horizontal position and having its upper surface formed to provide a pressing portion, said member also having a supplemental portion extending upwardly from the rear end of said body portion, the rear side of said supplemental portion being adapted to provide a supplemental pressing surface, and means for pivotally mounting the front end of said body portion so as to permit the same to be swung upwardly and forwardly to bring said supplemental pressing surface into position for use.

15 11. A pedal device having a pedal member provided with a body portion lying normally in a substantially horizontal position and having its upper surface formed to provide a pressing portion, said member also having a supplemental portion extending upwardly from the rear end of said body portion, the rear side of said supplemental portion being adapted to provide a supplemental pressing surface, and means for pivotally mounting the front end of said body portion so as to permit the same to be swung upwardly and forwardly to bring said supplemental pressing surface into position for use, and means for temporarily locking said pedal member in upwardly and forwardly adjusted position.

20 12. A pedal device having a pedal member provided with a body portion lying normally in a substantially horizontal position and having its upper surface formed to provide a pressing portion, said member also having a supplemental portion extending upwardly from the rear end of said body portion, the rear side of said supplemental portion being adapted to provide a supplemental pressing surface, means for pivotally mounting the front end of said body portion so as to permit the same to be swung upwardly and forwardly to bring said supplemental pressing surface into position for use, and means for temporarily locking said pedal member in upwardly and forwardly adjusted position, and also in lowered position.

25 13. A pedal device having a pedal member provided with a body portion lying normally in a substantially horizontal position and having its upper surface formed to provide a pressing portion, said member also having a supplemental portion extending upwardly from the rear end of said body portion, the rear side of said supplemental portion being adapted to provide a supplemental pressing surface, means for

30 pivotally mounting the front end of said body portion so as to permit the same to be swung upwardly and forwardly to bring said supplemental pressing surface into position for use, and means for temporarily locking said pedal member in upwardly and forwardly adjusted position, and also in lowered position, said means comprising a ball and apertures into which said ball may be introduced.

35 14. A pedal device comprising a pedal bar and a pedal member having its forward end pivoted to the forward end of the pedal bar, said pedal member having a body portion arranged in substantially horizontal position, and also having a supplemental portion extending forwardly from the rear end of said body portion, the rear side of said supplemental portion being provided with a pressing surface adapted to come into an elevated horizontal position when said pedal member is swung upwardly and forwardly about its pivoted end.

40 15. A pedal device comprising a pedal bar and a pedal member having the usual pedal shape and having its rear end extended upwardly to provide a supplemental pressing surface, said pedal member having its front end pivotally connected with the front end of the pedal bar.

45 16. A pedal device comprising a pedal bar and a pedal member having the usual pedal shape and having its rear end extended upwardly to provide a supplemental pressing surface, said pedal member having its front end pivotally connected with the front end of the pedal bar, and means for temporarily locking said pedal member in adjusted position.

50 17. A pedal device comprising a pedal bar and a pedal member having the usual pedal shape and having its rear end extended upwardly to provide a supplemental pressing surface, said pedal member having its front end pivotally connected with the front end of the pedal bar, and means for temporarily locking said pedal member in adjusted position, said means comprising a ball and an aperture on the pedal bar, and a plurality of apertures on a 110 pedal whereby said ball may be moved from one aperture to another.

55 18. A pedal device comprising a pedal bar and a pedal member having the usual pedal shape and having its rear end extended upwardly to provide a supplemental pressing surface, said pedal member having its front end pivotally connected with the front end of the pedal bar, means for temporarily locking said pedal member in adjusted position, said means comprising a ball and an aperture on the pedal bar, and a plurality of apertures on the pedal, whereby said ball may be moved from one aperture to another, and a spring tending nor- 130

mally to press said ball into said last mentioned apertures.

19. A pedal device comprising a pedal bar and a pedal member made hollow with a laterally widened front end, said pedal member having its front end pivotally mounted on the front end of the pedal bar by means of a pin passing through said pedal bar and also passing through said widened front end of the pedal member, a plate secured to one side of the pedal bar and extended laterally and then lengthwise of the pedal bar and located within the

widened front end or toe portion of said pedal member, a spring interposed between 15 said pedal bar and the end portion of said plate, said plate and pedal member being provided with apertures, and a ball capable of fitting into said apertures to cause a temporary locking of the pedal member in ad- 20 justed position.

In witness whereof, we hereunto subscribe our names this 7th day of February, A. D., 1919.

BENJAMIN H. JEFFERSON.
WALTER I. KIRK.
